UNITED STATES PATENT OFFICE.

CHARLES A. LINDSTRÖM, OF PITTSBURGH, PENNSYLVANIA, ASSIGNOR TO PRESSED STEEL CAR COMPANY, OF PITTSBURGH, PENNSYLVANIA, A CORPORATION OF NEW JERSEY.

CAR CONSTRUCTION.

1,230,183.

Specification of Letters Patent. Patented June 19, 1917.

Application filed April 9, 1914. Serial No. 830,716.

To all whom it may concern:

Be it known that I, CHARLES A. LINDSTRÖM, a citizen of the United States, residing at No. 138 Stratford avenue, Pittsburgh, 5 E. E., in the county of Allegheny and State of Pennsylvania, have invented certain new and useful Improvements in Car Construction, of which the following is a specification.

10 My invention relates to railway cars having wooden lining and flooring, and has particular reference to a novel side and floor construction suitable for use in box and gondola cars.

15 The particular object of my invention is to provide a construction of floor, and side and end lining for the above classes of cars, which will result in a car which will, without the use of an increased quantity of material, exclude moisture, prevent the leakage of grain or other granular lading, and prevent the outward bulging between the side posts of the lowermost boards of the lining, which if permitted leaves a space 25 between the flooring and lower side boards and consequent leakage of the lading, and which will permit of the removal of the floor boards for the purpose of repair or replacement, without the necessity of removing one or more of the side lining boards 30 which is essential in other constructions of this character with which I am familiar.

In the practice of my invention I contemplate the use of a metallic underframe, such 35 as is used in standard practice, having the usual center and side sills, bolsters, and cross bearers, and floor stringers of either wood or metal, combined with the construction of my invention to attain the aforementioned 40 objects.

The invention will be more readily understood by reference to the drawings accompanying this specification, in which like reference characters refer to like parts and 45 in which:

Figure 1 is a vertical cross section of a portion of a car taken near to the bolster member. Fig. 2 is an enlarged section of a portion of Fig. 1, showing more clearly the 50 construction of my invention. Fig. 3 is a cross section of a portion of a car showing a modification of my invention, and Fig. 4 is an enlarged section of a portion of Fig. 3.

Referring more particularly to the drawings, it will be seen that the underframe,

only one half of the width thereof being shown, consists of channel center sills 1, channel side sills 2, bolster members 3, and the usual crossbearers and end sills, the two last mentioned not being shown in the drawings. Side posts or stakes 4, and diagonal braces if necessary, extend upwardly at intervals and form the side framing of the car. The bolsters are shown as being composed of web plates 5, top and bottom stiffening members 6 and 7, and top and bottom tie plates 8 and 9, and are secured to the center sills 1, and side sills 2, in the usual manner. The floor 10 is supported by the floor stringers 11, which may be of wood as 76 shown in the drawings, or of metallic commercial sections, and extend substantially from end to end of the car.

When wooden stringers are used the flooring boards 10 may be nailed or bolted to the 75 stringers 11, or if metallic stringers of commercial section are used, the flooring boards may be bolted to them by bolts passing through holes in the stringers and flooring boards.

The end portions 12 of the flooring boards 10, are halved or reduced to about one half of their original thickness, such reduced portions extending for a distance, from the ends of the boards, sufficient to permit the reduced portions to rest on the wooden sub-sill 13, which rests on the side sill 2, and extends for the full length of the side of the car. The sub-sill 13, is of substantially Z shape in cross section, having at one side 90 a downwardly projecting portion 14, which engages the edge of the flange of the side sill 2, and at the opposite side an upwardly projecting portion 15 which engages with a groove 16 formed in the lower edge of the 95 lowermost side lining boards 17. The floor boards 10 may be secured to the sub-sill 13 by means of bolts 18 as shown in Figs. 1 and 2, or by means of nails 19 as shown in Figs. 3 and 4, or by a combination of bolts and 100 nails and the sides may be secured to the side posts by bolts 20 in the usual manner.

Figs. 3 and 4 illustrate a modification of my invention, in which the sub-sill member 13 has its upper surface 21 beveled or sloped. 105 and the reduced end portions 12 of the flooring boards 10, are also beveled so as to more easily insure a close contact with the beveled portion of the sub-sill.

It will be readily seen that the contact of 110

the downward projection 14 of the sub-sill 13, with the edge of the flange of the side sill 2, and the engagement of the upward projection 15 of the sub-sill 13, with the 5 groove 16 of the lower side lining board 17, forms an effective means for the prevention of bulging, between the side posts, of the side lining boards, and that the manner in which the sub-sill is combined with the floor 10 and side boards of the car enables a grain tight joint to be made and maintained.

It will be apparent that the construction just described for the floor and side walls, is also applicable to the end walls of the car, 15 and that modifications may be made in the construction described, and such modifications as are within the scope of my claims, are considered by me to be within the scope of my invention.

20 Claims:

1. In a railway car, the combination with the floor and side wall, of a side sill, a substantially Z section sub-sill resting on said side sill and interposed between said floor 25 and wall.

2. In a railway car, the combination with the side sill, and floor and side wall, of a substantially Z section sub-sill interposed between said floor and wall, said sub-sill engaging the flange of the side sill.

3. In a railway car, the combination with the side sill, and floor and side wall, of a substantially Z section sub-sill interposed between said floor and wall, said sub-sill en-

gaging the flange of the side sill to prevent lateral movement of the sub-sill on the side sill.

4. In a railway car, the combination with the side sill, and floor and side wall, of a substantially Z section sub-sill supported by 40 said side sill, said sub-sill engaging with a groove in said side wall, and with a rabbet in said floor.

5. In a railway car, the combination with the side and side sill, of a sub-sill having a 45 downwardly projecting portion engaging with said sill, and having an upwardly projecting portion engaging with said side, and flooring boards, the ends of which are rabbed and secured to said sub-sill.

6. In a railway car, the combination with the side sill and side, of a substantially Z-section sub-sill interposed between said side sill and side, and adapted to prevent lateral movement of the side.

7. In a railway car, the combination with the side sill and side, of a substantially Z-section sub-sill interposed between said side sill and side, and adapted to prevent lateral movement of the side, and a floor resting on 60 said sub-sill.

In testimony whereof I affix my signature in presence of two witnesses.

CHARLES A. LINDSTRÖM.
